WINDOW SILL ATTACHMENT

Vincenzo Ciscognetti, New York, N. Y.

Application January 2, 1935, Serial No. 161

8 Claims. (Cl. 155—198)

This invention relates to a structure which may be broadly referred to as an attachment for a window sill, and it has more specific reference to a device which is designed for home or domestic use and which serves a two-fold purpose.

One object is to provide what may be conveniently referred to as a padded elbow rest having supporting brackets hingedly attached to the window sill in such a way as to allow the rest to be swung above the window sill to permit the occupant of a window to comfortably support himself on his elbows while looking out of the window. Incidentally, it is common practice for persons, especially those in apartments and tenement houses to lean out of an open window for so called "sight-seeing" purposes. The present invention is to provide the occupant of the window a convenient elbow rest whereby while the occupant is in a bent over position greater comfort and convenience will be had.

An equally important object is to provide such an arrangement as serves not only as an elbow and arm rest but as a rack for so-called window boxes and flower stands and pots, etc.

Briefly stated then, I provide a padded board which serves in one instance as an elbow rest when the pad is up, and as a shelf when the pad is facing downwardly, attaching frames and hinge means provided to allow the device to be swung either into and above the window sill, or dropped outwardly down alongside of the wall of the building to serve as a satisfactory rack.

Other features and advantages will become more readily apparent from the following description and drawings.

In the drawings:

Figure 1 is a view partly in section and partly in elevation showing the invention and illustrating the manner in which it is swung into the window to serve as an arm or elbow rest.

Figure 2 is a bottom plan view of the device per se showing the frame arrangement and configuration.

Figure 3 is a horizontal sectional view taken approximately on the plane of the line 3—3 of Figure 1 looking downwardly in the direction of the arrow.

Figure 4 is a view similar to Figure 1 showing the device swung out of the window and hanging down in its rack forming position.

In the drawings, the numeral 5 designates the conventional window sill and in accordance with the present invention this is provided with a pair of attaching leaves or plates 6. These are fastened down on the window sill by screws or equiv-

alent fastenings 7. The outer end projects slightly beyond the corresponding edge of the window sill and is provided with a hinge knuckle 8 as shown in Figure 3. The central portion carries a swivelly mounted locking or turn button 9 having a T-head 10 which serves as a unique locking or retention device for the adjacent frame. There are two of these frames and they are denoted by the numeral 11 and are of general rectangular configuration. The longitudinal frame 10 members are distinguished by the numerals 12 and 13 while the transverse members are denoted by the numerals 14 and 15. The part 15 is slotted as at 16a to accommodate the adjusting and retaining bolts 16 which serve to fasten it to the shelf 17. Incidentally, in this connection it will be observed in Figure 1 that the wooden portion of the shelf has a nut 18 imbedded in it to accommodate the threaded shank of the bolt. Moreover it is evident that with this arrangement the shelf is adjustably connected to the frame through the instrumentality of this connecting bar or frame member 15. At the juncture of the parts 12 and 14 I provide a pair of hinge knuckles 19 attached by a pintle pin 20 to the aforementioned hinge knuckle 8. This serves to connect the frame to the attaching or anchoring leaves 6 so as to allow the double function of the frame. The connecting or frame member 14 is approximately the same in length as the attaching brackets 6 and is provided intermediate its ends with a transverse keeper slot 21 through which the T-head 10 passes after which it is turned as indicated in Figure 1 to hold the part 14 superimposed upon the attaching bracket 6. This in turn serves to secure the frames and the shelf in the window in superimposed relation above the window sill.

The shelf comprises a rectangular panel or board 22 of appropriate dimension and this is provided with a marginal metal frame or strap 23 which serves to secure in place a suitable arm pad 24.

It is evident that by providing a pair of simple attaching brackets 6, hingedly connecting the frames 11 thereto, and adjustably attaching the shelf to the frame, a unique assembly is thereby provided. When the parts are arranged as depicted in Figure 1 the invention serves as a convenient arm or elbow rest for the occupant of an open window for the purposes described. At this time, the swivelly mounted T-shaped fastener 10 serves to connect the frames to the attaching brackets and makes the structure rigid and avoids accident. Then by swinging the device out of

the window and dropping it down alongside of the wall of the building as shown in Figure 4 it functions as a convenient shelf or rack for plants, flowers and the like.

5 It is thought that persons skilled in the art to which the invention relates will be able to obtain a clear understanding of the invention after considering the description in connection with the drawings. Therefore, a more lengthy description 10 is regarded as unnecessary.

Minor changes in shape, size, and rearrangement of details coming within the field of invention claimed may be resorted to in actual practice, if desired.

15 Having thus described the invention, what is claimed as new is:

1. In a structure of the class described, a pair of substantially rectangular frames, a horizontally disposed board having adjustable connection with 20 said frames, said board being provided on one side with a padded arm rest, said frames having hinge means and certain of the bar members of the frames having keeper slots to accommodate a swivelly mounted headed fastening device.

25 2. In a structure of the class described, in combination, a pair of attaching brackets, each attaching bracket provided with a swivelly mounted turn button having a T-shaped retaining head, a pair of substantially rectangular frames hinged- 30 ly attached to the outer ends of said brackets, said frames including portions adapted to swing over the attaching brackets in overlapping relationship, said portions having keeper slots to accommodate the T-shaped locking head, a padded board, and bolt and nut means for adjustably connecting said board with the frames.

3. In a structural assemblage of the class described, in combination, a built-in window structure including a frame provided with a conventional 40 horizontally disposed window sill, one longitudinal edge of the sill projecting beyond the adjacent outer vertical edge portion of the window frame, a pair of transversely disposed attaching brackets secured one adjacent each end of the window sill, the outer ends of said brackets projecting beyond the aforesaid longitudinal edge 45 of the sill, a pair of hanger frames hingedly connected at corresponding corner portions to the outer ends of said attaching brackets to hang 50 vertically and downwardly at right angles to the window sill, and a horizontally disposed shelf adjustably and detachably connected at its opposite end portions to the lower ends of said depending hanger frames and constituting an article rack 55 for flower receptacles and the like, said hangers adapted to be swung into super-posed position on the brackets to support the shelf as an arm rest above the window.

4. In a structural assemblage of the class described in combination, a relatively stationary window structure including a frame having a horizontally disposed conventional window sill with one longitudinal edge thereof projecting beyond the adjacent vertical edge of the frame, a 65 pair of attaching brackets secured to the upper surface of the end portions of said sill and having hinge means at their outer ends located just beyond the projecting edge of the sill, a board of a length substantially commensurate with the 70 length of said sill, said board being plain on one side and formed with a cushioning pad on the other side, and a pair of double-acting brackets, said double-acting brackets being in the form of substantially rectangular frames with corresponding 75 corner portions thereof hingedly connected

to the outer ends of said attaching brackets, and means for adjustably and detachably connecting said board to predetermined side members of said double-acting frames, whereby to provide a two-purpose structure, the board serving in one instance as a flower rack during which time the frames constitute hangers therefor, and the padded side of board serving as an arm rest when the board is swung to a position directly above the window sill, during which time the frames 10 constitute risers and supports. 5

5. A multiple purpose convertible window sill attachment usable in one position as an arm and elbow rest and alternatively usable in another position as an article shelf or rack comprising 15 a longitudinally elongated board of predetermined dimensions, the board being plain on one side to serve as the aforementioned article shelf, and provided on the opposite side with padding constituting cushioning means when used in the 20 capacity of the aforesaid arm and elbow rest, a pair of end frames adjustably connected to the end portions of the plain side of said board and designed to serve either as hangers for the aforesaid shelf or vertical supports for the aforesaid arm rest as the case may be, and a pair of individual attaching brackets hingedly connected to corresponding corner portions of said end frames, said attaching brackets being designed for connection with the end portions of the complementary window sill and said end frames being adapted for disposition to superimposed relation on said brackets to support the board in an elevated position above the window sill when it is 35 used as an arm rest. 30

6. A combined elbow and arm rest for use temporarily in a conventional building window structure and adapted to be associated with the usual sill in said window structure, said attachment comprising a cushioned arm rest designed to occupy a horizontal position spaced vertically above the window sill when in use, said arm rest being suitably padded for comfort, end frames adjustably connected to the end portions of said arm rest, and means for connecting the end frames with the window sill to permit the arm rest to be readily brought into position for use or adjusted and moved to an out-of-the-way position when not in use. 40 45

7. A multiple purpose window sill attachment of the class described comprising a pair of attaching brackets intended to be rigidly connected with a window sill, the outer ends of the brackets being formed with hinge means designed to 55 project beyond the adjacent longitudinal edge of the sill, a pair of substantially duplicate rectangular frames superimposed upon said brackets and hingedly connected at corresponding corner portions to the outer ends of said brackets, manually adjustable and releasable retaining means between the attaching brackets and adjacent portions of the frames to hold said latter portions in the aforementioned superimposed positions on the attaching brackets or to allow said portions to swing out in a substantially horizontal plane even with the sill and attaching brackets when desired, and a board adjustably connected with said frames and designed to occupy a hanging horizontal position at right angles to the wall of the building or similar surface to function as an article rack or shelf, said board, when said frames are superimposed on the attaching brackets, being disposed in an elevated position 70 above the window sill. 75 90

8. A convertible two-fold window sill attachment of the class described comprising a longitudinally elongated board of a length substantially commensurate with the length of the complementary window sill, said board being plain on one side to function as a flower pot and article supporting shelf, and having its opposite side padded to function independently and successively as a cushioned arm rest, a pair of anchoring 5 and attaching brackets adapted for rigid con-

nection with the end portions of the companion window sill, and means adjustably connectible with the end portions of the plain side of said board to serve selectively as a hanger and/or a board elevating support, said means being hinged- 5 connected to the outer ends of said attaching brackets in the manner to permit said means to be disposed in superimposed positions on the brackets when the board is used as an arm rest.

VINCENZO CISCOGNETTI. 10
